METRIC SYSTEM 21

UNITED STATES PATENT OFFICE.

SAMUEL KELLETT, OF SAN FRANCISCO, CALIFORNIA.

DESIGN FOR CENTER-PIECE.

Specification forming part of Design No. **8,017**, dated January 19, 1875; application filed January 2, 1875.
 [Term of Patent 14 years.]

No. 5.

To all whom it may concern:

Be it known that I, SAMUEL KELLETT, of the city and county of San Francisco, State of California, have invented and produced a new and original Design for a Center-Piece in Basso-Rilievo, reference being had to the accompanying photograph and to letters marked thereon.

My new design consists of an oval drop, A, with radial figures B and C extending to a beaded border, D. Around this inner border D are placed flowers and stems E F G H, forming a continuous wreath. A plain bead, I, circles the wreath. The outer border is com-

posed of three distinct architectural designs, J, K, and L, combined together and completing the outer finish.

Having thus described my invention, what I claim, and desire to secure by Letters Patent, is—

The inner oval form A B C D, the wreath of flowers and stems, as shown, E F G H, and inside border J K L, as shown in photographs.

SAML. KELLETT.
